UNITED STATES PATENT OFFICE

2,131,838

INSOLE AND METHOD OF MAKING THE SAME

James P. Fredericksen, Wollaston, Mass., assignor to United Shoe Machinery Corporation, Paterson, N. J., a corporation of New Jersey

Application July 9, 1937, Serial No. 152,768

29 Claims. (Cl. 12—146)

This invention relates to insoles and methods of making insoles and is illustrated herein by way of example with reference to its use in the manufacture of welt shoes.

5 Objects of the invention as to provide improved methods of making insoles having lasting ribs thereon, and to provide improved insoles for shoes.

In accordance with one aspect or feature of the invention a relatively thin insole is provided at its marginal portion with a channel flap which varies non-uniformly in thickness widthwise, and the latter is turned back upon itself to produce on the insole an integral upstanding two-ply rib which varies in thickness heightwise. As herein illustrated, one form of channel flap may have a thick central or intermediate portion located, widthwise of the flap, between two relatively thin portions and the flap may be turned back and bent against itself adjacent to the thick central portion to produce an upstanding integral rib of the upper portion of which is bulged or knob-shaped in cross section so that it overhangs the base portion of the rib, which portion, being formed from the thinner portions of the flap, is relatively narrow. This construction produces substantial grooves or undercut portions at each side of the rib which greatly facilitate subsequent operations in constructing the shoe.

30 In accordance with another aspect of the method herein disclosed the feather portion of the insole is made thick enough to retain its flat condition in a shoe throughout the wear of the shoe, thereby assisting in holding the shoe upper in shape. As illustrated, the feather may be the full thickness of the body portion of the insole or it may be somewhat thinner than said body portion.

40 A further feature or aspect of the invention consists in providing as an article of manufacture an improved light-weight insole for use in welt or other types of shoes having at its marginal portion an integral upstanding rib which varies in thickness heightwise, the feather portion of the insole being at least thick enough to insure that the margin of the insole will remain substantially flat during the wear of the shoe so that the upper will retain its shape during such wear.

45 Modifications of the invention comprise providing insoles and methods of producing insoles having integral upstanding ribs thicker at their base portions than at their upper portions, thereby providing a thick "between substance" for the lasting and welt attaching operations, the feather portions of such insoles being as thick as their

body portions, and these modifications further comprise providing insoles and methods of producing insoles having integral lasting ribs which have bulged or knob-shaped upper portions overhanging narrower base portions, the feather portions of the insoles being thinner toward the edge of the insole than the body portions thereof so that the edge faces of the insoles are relatively narrow heightwise. This construction improves the appearance of the inside of the shoe by exposing only a relatively narrow edge face of the insole at the shank portion of the shoe where the curve or arch of the shoe bottom causes this edge face to show.

5 With the above and other features and aspects in view, the invention will now be described with reference to the accompanying drawing and will thereafter be pointed out in the claims.

In the drawing,

Fig. 1 is a transverse sectional view on an enlarged scale of an insole broken out at the center illustrating the method of forming a channel flap and a feather portion on the insole;

Fig. 2 is a sectional view similar to Fig. 1 after a lasting rib has been formed on the insole;

Fig. 3 is a sectional view of one side of the insole on a last with a shoe upper secured in last relation to the rib;

Fig. 4 is a sectional view similar to Fig. 3 after the welt attaching and inseam trimming operations have been performed.

Fig. 5 is a sectional view of the shoe with an outsole attached thereto;

Fig. 6 is a transverse sectional view of an insole illustrating a modification of the invention, one margin of the insole being channeled and trimmed to form a channel flap and feather portion and the other margin having a lasting rib formed thereon;

Fig. 7 is a sectional view similar to Fig. 5 after the insole of Fig. 6 has been incorporated in a shoe;

Fig. 8 is a transverse sectional view similar to Fig. 6 illustrating another modification of the invention; and

Fig. 9 shows the insole of Fig. 8 incorporated in a shoe.

45 In carrying out the method of the present invention an insole 10 of leather or artificial leather is cut out by dies or otherwise to substantially 50 the required shape but of a size which is from one-quarter to three-eighths of an inch larger than is to be required in the shoe. The material of the insole 10 may be of different thicknesses but it preferably ranges from three to three and 55

one-half irons. As shown in Fig. 1, the marginal portion of the insole is channeled inwardly from its edge face to produce a channel flap 12 and a reduced feather portion 14. Unlike the straight outside channel usually formed in an insole, however, the present channel is formed by a knife 16 having a cutting edge 18 which is shaped in the manner disclosed in Fig. 1, that is, the cutting edge is curved upwardly and downwardly relatively to the plane of the insole in arcs of substantially the same radii to produce an arched or undulating channel and a channel flap 12 which varies irregularly in thickness widthwise and which, in the present instance, is relatively thick at the central portion of its width and diminishes in both directions from said central portion to form thinner portions at each side thereof. The upper surface of the feather portion 14 is, of course, complementary to the adjacent surface of the channel flap, said upper surface having outer and inner rounded portions between which is located a relatively thin portion formed by a depression. The channel is wider than is usually formed in insoles for producing lasting ribs by an amount approximately equal to the amount larger that the insole was cut over the size which is to be utilized in the shoe, that is, from one-quarter to three-eighths of an inch.

Simultaneously with the cutting of the curved channel in the marginal portion in the insole the outer portion of the feather 14 is trimmed off by a vertical knife 20, thereby reducing the body portion of the insole to the size required for the shoe. Fig. 1 shows the channeling and trimming operations being performed on one side of the insole, and the other side of the figure illustrates how the insole will appear after these operations have been completed. The channeling and feather trimming operations may be performed manually or by machine, a convenient type of machine being that disclosed in Letters Patent of the United States No. 1,023,801, granted April 23, 1912 on an application filed in the name of Frederic E. Bertrand, this machine, however, being modified to omit the usual inside channel knife and the chamfering knife and to include the vertical knife 20 for trimming the feather portion of the insole to the required size.

After the channeling and trimming operations have been performed, the inner surface of the channel flap 12 and the adjacent or upper surface of the remaining portion of the feather 14 which, as pointed out above, is complementary to the inner surface of the flap, are coated with cement, preferably an instantaneous or quick setting cement such, for example, as latex or other cement having a rubber constituent. The channel flap is then turned upwardly and back upon itself, as shown in Fig. 2, to form an upstanding two-ply rib 22, this rib, as illustrated, being from one-eighth to three-sixteenths of an inch in height and varying in thickness heightwise by reason of the thick central portion of the flap, which in the present case forms a bulged upper portion somewhat knob-like in shape. The lower or base portion of the rib, having been formed from the thinner portions of the channel flap lying at each side of the thick central portion, is relatively narrow in cross section, thereby providing grooves or undercut portions 24, 26 at opposite sides of the rib, the inner groove 26 being well adapted to receive and guide the various operating instrumentalities of machines subsequently used in constructing a shoe such, for example, as the lasting, trimming and welt sewing machines, and the

outer groove 24 providing a crease into which the upper may be worked tightly against the base of the rib and in which the lasting staples and welt attaching seam may be conveniently located. The outer portion of the channel flap 12 which, owing to the peculiar shape of the channeling knife 16, is substantially complementary to the outer margin of the remaining portion of the feather 14, is turned outwardly and laid flat against this outer margin of the feather during the rib forming or shaping operation, and the cement between the parts secures the flap to the feather. Accordingly, the thickness of the reduced feather portion of the completed insole, as illustrated in Fig. 2, is restored to the original thickness of the marginal portion of the insole or, in other words, to the same thickness as the body portion of the insole located between the ribs 22.

In this way an insole is provided which may be only three or three and one-half irons thick and yet has an integral upstanding lasting rib the upper portion of which is bulged or knob-shaped in cross section so that it overhangs a relatively narrow base portion, thereby forming grooves or undercuts at both sides of said base portion, the outer groove being adapted to receive the shoe upper and the welt, and the inner groove being adapted to guide the operating instrumentalities of machines used in constructing the shoe, the feather portion of the insole, moreover, being substantially flat and equal in thickness to the body portion of the insole. A machine which may be used for performing the rib forming operation described above is that disclosed in United States Letters Patent No. 1,726,800, granted September 3, 1929, on an application filed in the name of F. E. Bertrand although other machines may be used or this operation may be performed by hand if desired.

If the material of the insole is of a good quality it can be used without a reinforcement on its outer face although it is customary on insoles of this type to reinforce the area between the ribs and also the inner sides of the ribs with fabric material such as Gem duck 28 (Fig. 3), this construction being commonly referred to as an "economy" insole. The reinforcement may, if desired, be applied during the rib forming operation with the aid of the machine of the type disclosed in the Bertrand patent mentioned above.

The insole 10, reinforced or not, as desired, is mounted on a last 30 and a shoe upper 32 is assembled and secured to the rib 22 in any usual manner to hold the upper in lasted position. Since the present invention is illustrated with reference to a welt shoe, the opposite sides of the upper 32 may be secured to the lasting rib by staples 34, this operation being preferably performed by a staple side lasting machine of the type disclosed in Letters Patent No. 1,731,853, granted October 15, 1929 on an application filed in the name of George Goddu. As shown in Fig. 3, the staples are inserted and clinched well down toward the base of the rib, this result being achieved by reason of the groove or undercut 26 at the inner side of the rib which receives the clinching anvil of the lasting machine and holds it close to the base of the rib wherever the staples are driven.

The toe and heel portions of the upper may be lasted in the usual manner and a welt 36 may be attached to the shoe bottom, as shown in Fig. 4, the inseam stitches 38 which secure the welt 75

passing below the staples 34 and, at the inner side of the rib, being located in the angle or groove 26. In the welt attaching operation, which is preferably performed on a machine of the type disclosed in Letters Patent No. 1,108,560, granted August 25, 1914, on an application filed in the name of Andrew Eppler, the curved needle and awl which insert the inseam stitches 38 are caused to pass through the between substance of the lasting rib below the staples 34 because of the position of the channel guide of the machine which, with an insole of the present construction, may be maintained in the angle at the extreme base of the rib by reason of the inner groove or undercut 26. Moreover, the upper may be worked tightly into the outer groove 24 thereby insuring a close bond or connection between the upper and the insole which greatly improves the strength and appearance of the shoe.

20 After the attachment of the welt 36 the shoe bottom is trimmed, as shown in Fig. 4, to remove the excess portions of the upper and, if necessary or desirable, the upper portion of the rib, thereby preparing the shoe bottom for receiving an outsole. The subsequent operations to complete the shoe may be performed in accordance with usual and well-known methods, filler material 40 (Fig. 5) being first applied to the shoe bottom between the trimmed portions of the rib, 25 and an outsole 42 being laid on the shoe bottom and attached by stitches 44 passing through the outsole and welt 36. The completed shoe, as shown in Fig. 5, has an insole which is much thinner than is customary in a welt shoe, thereby 30 tending to increase the flexibility of the shoe. Notwithstanding the light-weight insole, however, the shoe upper, welt and outsole are secured as firmly in position as though a heavier insole had been used. Moreover, the staples 34 35 and the inseam stitches 38 are both located in rows which are relatively even or uniform around the periphery of the shoe, that is, neither row rides upwardly on the rib at some portions of the shoe nor descends toward the base of the 40 rib at other portions. Consequently, there is no danger in the trimming operation of cutting away some of the staples which might, in other constructions, be located higher up on the rib than they should be, or of severing some of the 45 inseam stitches which likewise might be located too high on the rib.

Another way of forming an insole for use in shoes, more particularly welt shoes, is illustrated in Figs. 6 and 7, this method being a modification of that described above and including a further feature of the invention. In Fig. 6, an insole 46 is cut from three-eighths to one-quarter of an inch larger than is required in the shoe and is channeled on the outside in a manner similar to that already described except that the channel knife is shaped differently. In the present case a channel 48 is formed by a knife which is substantially parallel to the inner and outer surfaces of the insole 46 or, in other words, 50 to the plane of the insole from its edge face to a point adjacent to the inner end of the channel. From this point to the inner end of the channel the knife slants or curves downwardly preferably in a gradual non-uniform incline or an arc 55 of non-uniform radius so that the inner portion of the channel flap 50 which is thus produced is considerably thicker than its outer portion. As described above, the outer portion of the feather formed by the channeling operation is 60 cut off simultaneously with the formation of the

channel flap 50, thereby leaving a narrow feather 52 which, of course, is complementary to the inner portion of the channel flap.

The channel flap 50 and feather 52 are then 5 coated on their adjacent surfaces with cement and the channel flap is bent upwardly and folded back upon itself as described above to produce an upstanding two-ply rib 54 approximately one-eighth of an inch high, the lower or base portion 56 of the rib being somewhat thicker than its upper portion owing to the shape of the inner portion of the channel flap. This type of rib, therefore, has a base portion, usually referred to as a "between substance", which is thick enough to resist a substantial outward pull and consequently will be in no danger of tearing away from the body portion of the insole in cases where relatively heavy upper materials are used in the shoe. The outer portion of the channel flap is 10 bent outwardly and secured by cement to the remaining inner portion of the insole feather, thereby restoring this portion to its original thickness so that it will be relatively stiff in the shoe and will thus tend to retain its shape during the wear of the shoe and assist in maintaining 15 the shape of the upper material. It will be seen in Fig. 6 that the upper part of the lasting rib 54 is narrower than the base portion 56 and that the opposite sides of this upper part are substantially parallel to each other owing to the uniform thickness of the outer portion of the channel flap.

The insole 46 may then be mounted on a last 20 58, as shown in Fig. 7, a shoe upper 60 may be lasted to the rib by staples 62, a welt 64 attached by an inseam 66 located at the base of the rib, and filler material 68 and an outsole 70 applied to the shoe bottom in the usual manner, the outsole being permanently attached to the shoe by the out-seam stitches 72. As stated above, the outer surface of the insole between the rib 54 may be reinforced with canvas or the reinforcement may 25 be omitted, as desired.

It is desirable to have the shoe upper blend as closely as possible with the edge face of the insole inside the shoe, especially in the shank portion so that only a thin edge face of the insole will be exposed where the insole curves upwardly to conform to the shank portion of the foot. A further modification of the invention is illustrated in Figs. 8 and 9 which facilitates this result. A channel 74 is formed in a thin insole 76, the channel extending downwardly toward the inner surface of the insole on a substantial arc for a greater portion of its width for example, 30 three-quarters of its width, and then extending straight inwardly parallel to the plane of the insole for the rest of its width, this channel, as explained above, being substantially wider than is usual in ordinary insoles. The outer portion of the feather of the insole is cut away simultaneously with the formation of the channel 74, thereby leaving a relatively narrow feather portion 78 complementary on its upper side to the adjacent surface of a channel flap 80 formed by the channel 74. Cement is applied to the opposing surfaces of the channel flap and feather and the channel flap is turned up, as described, to form an upstanding two-ply rib 82, the upper portion of which is bulged or knob-like in cross section owing to the shape of the channel flap and the base portion of which for the same reason is relatively thin and converges inwardly at opposite sides to form grooves or undercuts 84, 86. The outer margin of the channel flap 80 is turned outwardly 35

and cemented to the complementary remaining portion of the feather thereby completing the construction of the insole. Since the outer portion of the channel flap 80 diminishes in thickness toward its edge face, and since the remaining portion of the feather of the insole likewise diminishes in thickness, as shown in Fig. 8, the combined thicknesses of the two portions when cemented together produce a feather portion on the insole which is somewhat thinner at the edge of the feather than the body portion of the insole and yet is substantially the full thickness of the insole adjacent to the rib so that the feather portion will remain flat in the finished shoe and will assist in maintaining the shape of the shoe during its wear. As shown in Fig. 8, the reduced feather portion 78 tapers downwardly toward the edge face of the insole thereby leaving a relatively thin or narrow edge face.

Fig. 9 illustrates a shoe in which the insole of Fig. 8 has been incorporated and it will be seen that, owing to the reduced feather 78 which leaves a relatively narrow edge face on the insole, the upper 86 of the shoe will blend more smoothly with the edge face of the insole when the last is removed than is possible in a shoe having an unreduced feather. In other words an edge face the full thickness of the insole will not show at the shank portion of the shoe where the curve of the insole causes this edge face to be exposed.

While the invention has been described herein with reference to the manufacture of welt shoes, it should be understood that the invention is not limited to shoes of that construction since it may be utilized to advantage in all types of shoes in which a lip or rib is used for holding the upper in lasted position and also where it is desired that the means securing the upper to the rib or at least a portion of such means remain permanently in the shoe bottom to increase the strength of the shoe.

Having thus described my invention, what I claim as new and desire to secure by Letters Patent of the United States is:

1. That improvement in methods of making insoles which comprises forming at the marginal portion of an insole a single channel flap which varies non-uniformly in thickness widthwise, and turning the non-uniformly varying channel flap back against itself to produce on the insole an integral upstanding rib which varies in thickness heightwise.
2. That improvement in methods of making insoles which comprises separating from the marginal portion of an insole a channel flap of non-uniformly varying thickness widthwise, thereby reducing the thickness of said marginal portion, folding a non-uniformly varying portion of the channel flap back against itself to produce on the insole an upstanding rib of different thicknesses heightwise, and securing the rest of the channel flap to a reduced portion of the insole from which the flap was separated, thereby increasing the thickness of said portion.
3. That improvement in methods of making insoles which comprises forming at the marginal portion of an insole an outside channel flap having thick and thin portions widthwise of the flap, said portions producing a flap which varies irregularly in thickness over its entire width, bending the inner portion of said irregularly varying flap back upon itself to produce on the insole an upstanding rib which varies in thickness heightwise, and laying the outer portion of the flap flat against the marginal portion of the insole.

4. That improvement in methods of making insoles which comprises cutting in the marginal portion of an insole an outside channel which curves unevenly out of the plane of the insole widthwise of said marginal portion, thereby producing on the insole a channel flap and a reduced feather both of which vary unevenly in thickness widthwise from their inner portions to their outer portions, removing an outer portion of said feather, bending an inner portion of the channel flap back into contact with itself to produce an integral upstanding rib which varies in thickness heightwise, and securing an outer portion of the flap to the remaining portion of said feather thereby increasing its thickness.

5. That improvement in methods of making insoles which comprises forming at the marginal portion of an insole an outside channel flap which varies non-uniformly in thickness widthwise from its inner edge to its outer edge, thereby producing on the insole a reduced feather portion which likewise varies non-uniformly in thickness widthwise from its inner edge to its outer edge and is complementary to said channel flap, the outer portion of said flap being also complementary to an inner portion of said feather and being of a thickness which will combine with the inner portion of said feather to equal the full thickness of the insole, trimming off the outer portion of said feather, turning an inner non-uniformly varying portion of said channel flap back into contact with itself to produce an integral upstanding rib which varies in thickness heightwise, and securing the outer portion of said channel flap to the complementary inner portion of said feather, thereby restoring the inner portion of said feather to the original thickness of the insole.

6. That improvement in methods of making insoles which comprises cutting in the marginal portion of an insole an outside channel of substantial width which inclines in non-uniform progression toward the inner surface of the insole widthwise of the channel, thereby producing on the insole a reduced feather and a channel flap both of which have thick and thin portions widthwise thereof, said portions varying non-uniformly in thickness in their widthwise variation, trimming off the outer portion of said feather, and folding the channel flap back upon itself at a portion thereof having both thick and thin portions of non-uniform variation and securing said portion in such a position to produce an integral upstanding rib on the outer surface of the insole, said rib being thicker at some portions than at others.

7. That improvement in methods of making insoles which comprises forming at the marginal portion of an insole a channel flap having a relatively thick central portion located between thinner portions widthwise of the flap, and bending the channel flap back upon itself to produce on the insole an integral upstanding rib the upper portion of which is thicker than its base portion.

8. That improvement in methods of making insoles which comprises forming at the marginal portion of an insole an undulating channel which arcs toward the inner surface of the insole at the central portion of the channel and arcs toward the outer surface of the insole at each side of said central portion, thereby producing a single channel flap having a thick central portion and thin portions at each side of said central portion, bending the channel flap back upon itself adjacent to its thick central portion, and securing the

flap in such position to form an upstanding rib having a knob-shaped upper portion overhanging a relatively narrow base portion.

9. That improvement in methods of making in-

soles which comprises forming at the marginal portion of an insole a channel flap having a relatively thick central portion widthwise of the flap and thinner portions each side of said thick portion, and bending the channel flap back upon itself to form on the insole an integral upstanding rib having a relatively thick upper portion overhanging the inner side of a thinner base portion, thereby producing a groove at the inner side of said base portion.

10. That improvement in methods of making insoles which comprises cutting at the marginal portion of an insole a channel which inclines toward both the inner and outer surfaces of the insole at different portions of its width, thereby producing a channel flap which varies in thickness widthwise, and turning the channel flap back upon itself adjacent to its thickest portion to form an upstanding rib having a bulged upper portion overhanging the outer side of a narrower base portion, thereby producing a groove at the outer side of said base portion.

11. That improvement in methods of making insoles which comprises cutting at the marginal portion of a relatively thin insole an outside channel of greater width than usual and curving upwardly and downwardly in arcs of substantially equal radii toward the outer and inner surfaces of the insole to form a channel flap which is relatively thick at the central portion of its width and is relatively thin at each side of said central portion, thereby leaving a reduced feather on the insole which is complementary in shape to the inner surface of the channel flap, cutting off an outer portion of the feather of the insole, bending the channel flap back upon itself adjacent to its thick portion and cementing it in such position to produce an upstanding rib having a bulged upper portion overhanging a thinner base portion, thereby producing definite grooves at each side of said rib, and turning the outer portion of the channel flap outwardly and cementing it flat against the remaining portion of the complementary feather with the edge faces of said portions substantially flush, thereby producing a feather on the insole which is equal in thickness to the body portion thereof.

12. That improvement in methods of making insoles which comprises cutting in the marginal portion of an insole a channel which curves in an arc of non-uniform radius toward the inner surface of the insole near the end of the channel thereby producing a channel flap having an end portion thicker than the rest of said flap, and bending the channel flap including the thicker end portion back into contact with itself to produce an upstanding rib the base portion of which is thicker than its upper portion.

13. That improvement in methods of making insoles which comprises forming at the marginal portion of an insole a channel flap of substantial width an end portion of which curves toward the inner surface of the insole, and turning the channel flap back against itself and securing it in upstanding position to form an integral rib having a relatively thick base portion supporting a relatively thin upper portion the opposite sides of which are substantially parallel.

14. That improvement in methods of making insoles which comprises cutting in the marginal portion of an insole an outside channel of sub-

stantial width and extending at its outer portion parallel to the inner and outer surfaces of the insole and at its inner portion curving toward the inner surface of the insole, thereby producing a channel flap and a reduced feather portion on the insole, cutting off the outer portion of the feather of the insole, bending the channel flap back upon itself and cementing it in such position to form an upstanding rib the upper portion of which is thinner than its base portion, and securing the outer portion of the flap flat against the remaining feather portion of the insole, thereby making said feather portion as thick as the rest of the insole.

15. That improvement in methods of making insoles which comprises forming at the marginal portion of an insole a channel of substantial width which extends laterally of the insole in an arc and has a straight end portion substantially parallel to the plane of the insole, thereby producing a channel flap having a thick portion which gradually diminishes in both directions widthwise of the flap and having an end portion of uniform thickness which is thinner than said thick portion, and bending the thick portion of said channel flap back upon itself to produce an upstanding integral rib the upper portion of which is knob-like in shape and overhangs a relatively narrow base portion.

16. That improvement in methods of making insoles which comprises forming at the marginal portion of a relatively thin insole an outside channel flap of substantial width, said channel flap having an arced outer portion which increases and diminishes gradually in thickness and having an inner portion of uniform thickness equal to the thinnest part of said arced outer portion, thereby producing on the insole a feather portion complementary in shape to said channel flap, bending the channel flap up and back upon itself adjacent to its thickest portion to produce an upstanding rib having a thick, knob-shaped upper portion and a base which is thinner than said upper portion and is undercut on both sides relatively thereto, and securing the remaining outer portion of the flap flat against a complementary portion of the feather of the insole, thereby increasing the thickness of said feather portion but leaving its edge face thinner than the body portion of the insole due to the gradually diminishing thickness of said outer portion.

17. That improvement in methods of making insoles which comprises cutting in the marginal portion of an insole a relatively wide outside channel which curves in an arc toward the inner surface of the insole at the outer portion of the channel and extends parallel to the plane of the insole at its inner portion, thereby producing a channel flap having a convex inner side and a straight outer side and a feather portion having a concave outer side opposing said convex side, cutting away the outer portion of the insole feather, bending said channel flap back upon itself adjacent to its thickest portion to produce an upstanding rib having a knob-shaped upper portion overhanging a narrow base portion, thereby providing substantial grooves at the opposite sides of the base of the rib for facilitating the lasting, trimming and sewing operations in constructing a shoe, and securing the outer portion of the channel flap flat against a remaining complementary portion of the insole feather with the edge face of said flap flush with the edge face of said feather, thereby restoring a portion of said

- feather to its original thickness but leaving its edge face of less thickness than the body of the insole.
18. An insole having at its marginal portion an upstanding two-ply rib formed from a single layer of material integral with the insole, said rib varying in thickness heightwise.
19. An insole having at its marginal portion an upstanding lasting rib comprising two layers of material formed from a single layer of material integral with the body portion of the insole, said rib varying in thickness heightwise, said insole having a feather portion at least a part of which is as thick as the body portion of the insole.
20. An insole having at its marginal portion a two-ply rib composed of a single continuous layer of material integral with the body portion of the insole, said rib being thicker at some portions heightwise thereof than at other portions, said insole having a feather thereon which is composed of a portion of said continuous layer combined with a portion of the body of the insole.
21. An insole having at its marginal portion an integral upstanding rib composed of two plies of material secured to each other, the upper portion of the rib being thicker than its base portion.
22. An insole having at its marginal portion an upstanding two-ply rib composed of a single layer of material integral with the insole, the upper portion of said rib being thicker than its base and overhanging the outer side of said base, thereby producing a groove at the outer side of said base.
23. An insole having at its marginal portion an upstanding two-ply rib formed from a single layer of material integral with the insole, the upper portion of said rib being bulged relatively to its base portion and overhanging the inner side of said base portion, thereby producing a groove at the inner side of said base portion.
24. An insole having at its marginal portion an upstanding rib formed from a single layer of material integral with the insole and doubled over upon itself to produce a two-ply rib, said rib having a knob-shaped upper portion of substan-
- tial thickness overhanging both sides of a narrower base portion, thereby producing inner and outer grooves at said base portion.
25. An insole having at its marginal portion an integral upstanding rib comprising two layers of material, the top portion of the rib being knob-shaped in cross section and overhanging a relatively narrow base portion, thereby providing grooves at opposite sides of said base portion for facilitating the lasting, trimming and sewing operations in constructing a shoe, said insole having a feather portion which is equal in thickness to the body of the insole.
26. An insole having at its marginal portion a two-ply upstanding rib of material integral with the insole doubled over upon itself, said rib having an upper portion of substantially uniform thickness supported by a thicker base portion.
27. A relatively thin insole having at its marginal portion an integral upstanding two-ply rib formed from a single continuous layer of material partially separated from the insole and turned back upon itself, said rib being thicker at its base portion than at its upper portion and said upper portion being substantially uniform in thickness, said insole also having a feather portion equal in thickness to the body portion of the insole.
28. An insole having an upstanding two-ply rib formed from a single continuous layer of material integral with the insole, said rib having a bulged upper portion overhanging a relatively narrow base portion, said insole having a feather portion the edge face of which is less than the thickness of the body portion of the insole.
29. An insole having an upstanding two-ply rib integral with the insole and formed from the single flap of an outside channel, said rib being thicker at its upper portion than at its base portion, said insole also having a feather the inner portion of which is equal in thickness to the body portion of the insole and the marginal portion of which is thinner than the body portion of the insole.

JAMES P. FREDERICKSEN.
